(57) CLAIM

The ornamental design for a display screen with graphical user interface, as shown and described.

DESCRIPTION

FIG. 1 is a front view of a display screen with graphical user interface showing our new design; and, FIG. 2 is an enlarged view of the rectangular element in the lower central portion thereof. The broken line showing of the content, the avatar, the scenery, the remainder of the user interface and the remainder of the display screen is for environmental purposes only and forms no part of the claimed design.
